JUSTUS J. ROSS, OF HUNTINGTON, WEST VIRGINIA

MINE-TIE CLIP

Application filed April 23, 1929. Serial No. 357,493.

This invention relates to fastening or anchoring means for rails and has special reference to clips for use on metallic mine ties.

One of the objects of the present invention 5 consists in the provision of rail fastening clips which are so designed as to be used for clamping seven different sizes of rails and which will at the same time maintain the proper gauge of the track within practical limits.

10 A further object of the invention resides in the use of clips so designed as to permit the insertion of a tie as a replacement in a track already laid, or which will permit the individual removal of a tie.

15 Another object of the invention consists in the provision of clips which may be riveted to the tie and which may be placed close to the rail base thereby decreasing the amount of material used in the clips.

20 A further object of the invention resides in provision of pairs of clips, one clip of each pair serving as a gauging clip and provided with one or more squared faces, while the other clip serves as a tightening or fastening 25 clip and is provided with faces in the form of arcs and tangents which cooperate with the base or web of the rail or both, so as to secure the rail in place; the arc and tangent faces transmitting pressure directly to the 30 center of the rivet which forms the pivot of the clip and thus avoiding any tendency to move the clip to unlocking position.

Other objects and advantages of the invention will be apparent from the following description when taken in connection with the 35 accompanying drawings, in which

Figure 1 is a fragmentary longitudinal section through a tie showing one form of rail securing clips.

40 Figure 2 is a plan view of the construction shown in Figure 1.

Figure 3 is a plan view of a modified construction of clips.

Figure 4 is a section through the clips of 45 Figure 3.

Figure 5 is a plan view of a further modified construction.

Figure 6 is a plan view of a still different form of clips.

50 Figure 7 is a section through the clips of

Figure 6 showing the same in position for securing a 40 pound rail in place.

Figure 8 is a plan view of a slightly modified construction; and

Figure 9 is a section through the clips of 55 Figure 8, also showing the clips in position for securing a 40 pound rail.

The present invention may assume many different forms and it is to be understood that the several forms depicted on the drawings are merely illustrative of only a few of such forms, the invention being generic to these forms as well as many others not disclosed herein; and it is intended that the claims appended hereto shall include within 60 65 their scope all such constructions.

Referring to the drawings in greater detail and especially to Figures 1 and 2, the numeral 1 indicates a metallic mine tie of any conventional construction and provided with 70 a reinforcing plate 2 on which the base of the rail 3 is adapted to rest. This plate is riveted to the upper surface of the tie by means of rivets 4 and 5, the latter also serving as pivots for the rail clips 6 and 7 which 75 will be presently described. The plate 2 is provided with downturned flanges which are also secured to the tie by means of rivets 8 thereby providing a tie of sturdy construction which is adapted to heavy duty in mines 80 as well as to general railroad use.

Referring now to the rail anchoring clips and especially to clip 6, the body is formed of a flat portion 9 in contact with the upper surface of the tie and an upwardly inclined portion 10 which is spaced from the tie. This clip may be termed a gauging clip in contradistinction to the clip 7 which serves as a tightening and locking clip. The flat portion 9 of the clip 6 is provided with two rail 90 engaging faces 11 and 12. These faces are squared and are adapted to engage the straight edge of the base of rails of different sizes, while the inclined portion 10 overlaps the base of the rail. The inclined portion 10 is also provided with two engaging faces 13 95 and 14 adapted to engage the web portion 15 of rails of different sizes. In some instances the rail may be engaged by the gauging clip at both the edge of the base and the web por- 100

tion 15 of the rail. This clip, as previously stated, is pivoted to the tie by its anchoring rivet 5 and is provided with a spring latch portion 16 which is adapted to cooperate with 5 openings 17 formed in the reinforcing plate 2 and tie 1. By means of this latch 16 and perforations 17 the gauging clip 6 may be locked in either of its rail engaging positions.

10 The clip 7 which serves to engage the opposite side of the rail is a tightening clip. This clip also is provided with a flat portion 16 in engagement with the upper surface of the reinforcing plate 2 and an inclined portion 17 which is spaced from the tie so as to overlap the base portion of the rail. As will be clear from an inspection 15 of Figure 2 the flat portion 16 is provided with a plurality of flattened rail engaging faces 18 adapted to engage the edge of the base of rails of varying sizes, while the inclined portion 17 is also provided with a plurality of rail engaging faces 19 adapted to engage the web 15 of rails of different sizes; and 20 in some instances the rails may be engaged by the faces of both the flat portion 16 and the inclined portion 17.

It is to be particularly noted that the rail 30 engaging faces 19 and 13 of the clips 6 and 7 are arranged as tangents of circles having their centers at the pivot points of the clips 6 and 7. By reason of this tangential arrangement of the locking faces of the clips it will be apparent that there is no tendency for the 35 clips to be forced to unlocking position by reason of pressure from the rail, since the pressure is directed toward the centers of the pivot points of the clips. The clip 7 is also provided with means for locking the same in its several positions; such means taking the form of a plurality of apertures 20 formed in the reinforcing plate 2 and tie 1 which serve to receive the lug 21 which is formed on the remote end of the clip 7. Also formed 40 on the reinforcing plate 2 are a pair of stops 22 and 23 which cooperate with the clip 7 to limit its movement in one direction.

To hold the ties in proper alignment so as 50 to prevent shifting of the track either on curves or straight way, I have provided alignment lugs 24. These lugs in the present form of the invention are formed by providing sharpened points on the lower heads of the rivets 5 which secure the clips 6 and 55 7 to the tie and these sharpened points 24 dig into the ground and anchor the tie in its proper position, thereby preventing shifting of the track.

The construction of tie and locking clips 60 shown in Figures 1 and 2 is strong and durable and is therefore adapted to use in the general construction of railroads as well as in the laying of mine tracks. It will be noted also that with this type of rail engaging clips 65 a tie may be "spotted" in a track, that is to

say, by swinging the clips so that their straight longitudinal edges extend transversely of the tie, the latter may be slipped under the rails in place of a worn out tie and the clips then turned to proper position to lock the rails to the tie. It will also be noted that the clips as just described will function to lock in proper position or gauge 70 seven different sizes of rails by reason of the plurality of faces which are formed on the flat and inclined portions of these clips. 75

In the form of the invention shown in Figures 3 and 4 the clip 30, which is the gauging clip, is also provided with a flattened portion 31 adapted to engage the surface of the tie and an upwardly inclined portion 32 adapted to overlap the base of the rail and each of these portions is provided with a squared face for engaging respectively the edge of the base portion or the web of the rail or both. The face of the flat portion 31 of this gauging clip engages the large size rail (30, 40 and 45 pounds) on the base and the face of the inclined portion 32 gauges the smaller rails by engagement with the web of 80 the rail. The tightening clip in this form of the invention is indicated by the numeral 33 and is likewise provided with a flattened portion 34 for contact with the tie and an upwardly inclined portion 35 adapted to 85 overlap the base of the rail. 90

As in the previously described form the flat portion 34 of the tightening clip is provided with a plurality of rail engaging faces 36 and the inclined portion 35 is provided with a plurality of rail engaging faces 37. Certain of the faces 36 and 37 have portions 95 thereof formed as tangents of circles having the pivot of the clip as the center. These tangential portions are indicated by the numeral 38 and merging into these tangential faces are the tightening faces 39 which are curved in the form of an arc or spiral. By this arrangement it will be apparent that as the clip 33 is rotated into locking position 100 for the particular size of rail with which it is at the time cooperating, the curved or spiral portion 39 will engage against the web or base of the rail as the case may be, and force the rail into engagement with the gauging clip 30. Further movement of the tightening clip will then bring the tangential or locking faces 38 into squared engagement 105 with the rail. The fact that the squared or locking faces 38 of the tightening clip are tangential to circles having the clip pivot as the center, will cause any force applied to this portion of the clip to be directed to the center of the rivet which forms the pivot for the clip, thereby avoiding any tendency of pressure on the rail to swing the clip to an 110 unlocking position. 115

For the purpose of rotating the clip 33 I provide lugs 40 which may be engaged directly by a hammer or the like, or a fish plate 120

or angle bar may be laid against the edge of the lugs 40 and in turn receive the blows of a hammer or other instrument for rotating the clip to locking or unlocking position.

5 The rail securing clips just described and disclosed in Figures 3 and 4 are intended for a somewhat lighter service than those disclosed in Figures 1 and 2, and while they have all the advantages of the first described 10 clips, such as spotting of a tie and the like, it is not deemed necessary in this form to provide a special lock for the clips, such as the pins 17 and 21, for the reason that the tangential locking faces of the tightening 15 clip prevent any tendency of the clip to move to unlocked position. This latter form of locking clips also has the advantage that it is "fool-proof" in the sense that there is only one position for the gauging clip 31, thereby eliminating any possibility of the 20 operator moving this clip to an improper position for any size of rail.

In Figure 5 is shown a pair of rail securing clips which are substantially the same as those just described and shown in Figures 3 and 4; the difference being that the clip 50 is a tightening clip rather than a gauging clip, while the clip 51 is a gauging clip. In this connection it will be noted that the clip 30 50 has its two rail engaging faces 52 and 53 formed of compound portions which merge together, that is to say, each of these faces is provided with a face which is tangential to a curve having the pivot point at its center and with a spiral or arcuate face which merges into the tangential face. In the gauging clip 51, which is provided with the plurality of rail engaging faces 54 and 55, the spiral or arcuate faces are omitted inasmuch 35 as the tightening function is performed by the clip 50. The faces 54 and 55 of the clip 51, however, are formed on tangents of a circle having the rivet as its center.

In Figures 6 and 7 is shown a still further modified form of the rail securing clips and in this form, which is adapted to secure a more accurate gauge of the track, the gauging clip 60 which is pivoted to the tie by means of the rivet 61, is provided in addition to the flat tie contacting portion 62, with four upwardly inclined portions 63 which are spaced from the upper surface of the tie. The flat portion 62 as well as the upwardly inclined portion 63 is provided with squared 50 rail engaging faces adapted to engage the web or base of rails of varying sizes; the faces being spaced from the pivot points varying amounts for this purpose. In this modified form of the invention the tightening clip 55 is indicated by numeral 64 and is provided with the flat tie engaging portion 65, the upwardly inclined portion 66 and operating lugs 67.

7 Seven rail engaging faces are provided on 60 the flattened portion 65; these faces being

formed of arcs and tangents as previously described in connection with other forms to first tighten the rail into proper gauging relation with the gauging clip and then locking it in such position by means of the related tangential face. This construction of rail securing clips provides for the fastening of seven different sizes of rails and due to the plurality of gauging faces, provides for a more accurate gauging of the rails. Furthermore, in this form of the invention the clips are so designed as to gauge and tighten the rails solely by contact with the base of the rails, thereby greatly reducing the amount of material required in forming the clips since it is not necessary that the clips extend so far as to contact with the web of the rail as in the previously described forms.

Figures 8 and 9 disclose a further modified form of development of the rail securing clips, being substantially a reversal of the construction shown in Figures 6 and 7. In this modified form the tightening clip, indicated by the numeral 70, is provided with the flat tie engaging portion 71 and the four upwardly inclined portions 72 adapted to engage over the base of the rail. The flattened portion of the clip 70 is provided also with four rail engaging faces 73 which are formed of spiral and tangential faces as described in connection with other forms so as to first tighten the rail and then lock it against the gauging clip. The gauging clip, which is indicated by the numeral 74, has the flattened portion 75 for contacting the top of the tie and the upwardly inclined portion 76 which is spaced above the tie so as to overlap a portion of the rail base. The flattened portion of this gauging clip is provided with a plurality of rail engaging faces 77 which are tangential to a circle, having the pivot point of the clip as its center. The clip 74 is shown as being integrally formed with a rivet 77 which is shown as provided with a head 78. It will be understood, that this construction is merely illustrative of a modified means for securing the clips to the tie in lieu of the separate rivets shown in connection with the forms previously described.

In this form of the invention shown in Figures 8 and 9 the clips provide a very accurate gauge of the rails and their cost of manufacture is reduced due to the fact that the amount of material used in the clips is greatly reduced over that shown in Figures 1 to 5 inclusive, in which the clips are adapted to engage the web portion of certain sizes of rails.

From the foregoing description taken in connection with the accompanying drawings, it will be observed that I have devised a variety of means for securing rails to cross-ties; that the embodiments shown are merely concrete examples of a variety of forms of clips in which the present invention may be em-

bodied; that by reason of the riveting of the clips the same may be placed closer to the rails and thus reduce the amount of material required in the construction of clips; that by reason of their design a gauging of the rails of a plurality of sizes is possible; that the clips clamp the base of the rail so as to prevent the tie from sliding along the rail; and that the construction is such as to permit the insertion and withdrawal of ties from a track already laid without in any way disturbing the track.

Having fully described my invention, what I claim as new and desire to secure by Letters Patent is:

15. 1. Means for securing a rail to a tie, said means including a pair of pivotally-mounted clips, one of said clips provided with a squared face to engage the web of a rail, and the other clip provided with a face partly squared and partly formed of a compound curve.
20. 2. Means for securing a rail to a tie, said means including a pair of pivotally-mounted clips, one of said clips provided with a squared face to engage the base of a rail, and the other clip provided with a face, a portion of which is tangent to a circle about its pivot and another portion of which is a spiral.
25. 3. Means for securing a rail to a tie, including a gauging clip, and a pivotally-mounted tightening clip, said tightening clip provided with one or more tightening faces and one or more locking faces.
30. 4. Means for securing a rail to a tie, including a gauging clip, and a pivotally-mounted tightening clip, said tightening clip provided with a tightening face and a locking face which merge together.
35. 40. 5. Means for securing a rail to a tie, including a gauging clip, and a pivotally-mounted tightening clip, said tightening clip provided with a tightening face of arcuate contour and a locking face tangential to a curve having the pivot of the clip as its center.
45. 6. Means for securing a rail to a tie, said means including a gauging clip, and a pivotally-mounted tightening clip, said tightening clip provided with a flat portion in contact with the tie and an inclined portion spaced from the tie, each of said portions having its edge provided with a tightening face and a locking face.
50. 55. 7. Means for securing a rail to a tie, said means including a gauging clip, and a pivotally-mounted tightening clip, said tightening clip provided with a flat portion in contact with the tie and an inclined portion spaced from the tie, each of said portions having its edge provided with a plurality of tangential locking faces, and one or more tightening faces of spiral formation merging into certain of said tangential locking faces.
60. 65. JUSTUS J. ROSS.
